UNITED STATES PATENT OFFICE.

OTIS A. MYGATT, OF NEW YORK, N. Y.

DESIGN FOR A SHADE, REFLECTOR, OR SIMILAR ARTICLE.

No. 40,182.

Specification for Design.

Patented July 27, 1909.

Application filed June 5, 1908. Serial No. 437,019. Term of patent 14 years.

To all whom it may concern:

Be it known that I, OTIS A. MYGATT, a citizen of the United States, residing at New York, in the county of New York and State of New York, have invented a new, original, and ornamental Design for a Shade, Reflector, or Similar Article, of which the following is a specification, reference being had to the accompanying drawing, forming part thereof.

The drawing is a perspective view of a shade or reflector embodying my invention.

The design is represented by a shade or

reflector having four flat sides flared out from the collar. Connected with the flared sides are vertical flat sides. The outside of the shade or reflector is covered with radially arranged and vertically disposed prisms.

I claim:

The ornamental design for a shade, reflector, or similar article, as shown and described.

OTIS A. MYGATT.
